United States Patent Office

Des. 195,568
Patented July 2, 1963

195,568

CLOTHES SUPPORT

Harold Gleitsman, New Rochelle, and Carl Fuerst, Bronx, N.Y., and John H. Squadra, Westport, Conn., assignors to Gleitsman's, Inc., Long Island City, N.Y., a corporation of New York

Filed Nov. 30, 1962, Ser. No. 72,663

Term of patent 14 years

(CL. D33—8)

FIG. 1

FIG. 2

FIG. 3

FIG. 4

FIG. 5

FIG. 1 is a front perspective view of the clothes support showing our new design;

FIG. 2 is a front elevational view thereof;

FIG. 3 is a side elevational view thereof;

FIG. 4 is a top view thereof; and

FIG. 5 is a bottom view thereof.

We claim:

The ornamental design for a clothes support, substantially as shown.
